UNITED STATES PATENT OFFICE.

LUCIUS T. SHEFFIELD, OF NEW YORK, N. Y.

DENTAL ENGINE.

SPECIFICATION forming part of Letters Patent No. 408,439, dated August 6, 1889.

Application filed July 6, 1888. Serial No. 279,175. (No model.)

To all whom it may concern:

Be it known that I, LUCIUS T. SHEFFIELD, of the city, county, and State of New York, have invented a new and useful Improvement 5 in Dental Engines, of which the following is a full, true, and exact description, reference being had to the accompanying drawings.

My invention relates to a simplified form of dental engine by means of which the structure can be greatly cheapened and the backlash of the tool-holder to a great extent avoided.

My apparatus will be readily understood from the accompanying drawings, in which—

15 Figure 1 represents an elevation; Fig. 2, a section of the engine proper, showing the attachment of the flexible cable; Fig. 3, the flexible cable; Fig. 4, a detail of the sectional view of the mechanism for connecting the 20 fly-wheel with the driving mechanism; Fig. 5, a sectional view through the adjusting mechanism at right angles to Fig. 4, and Figs. 6 and 7 views of a modification.

My drawings show a fly-wheel A mounted 25 upon a suitable frame-work and driven by a treadle B. The tool-driving mechanism consists of a rotating shaft C, to the upper end of which the cable D is attached. The shaft C is driven, preferably, by frictional contact 30 with the side of the fly-wheel A, the lower end of the shaft C being provided with a friction-roller E. The friction or pressure between the friction-roller E and the side of the fly-wheel A can be readily adjusted by the mechanism shown in Figs. 4 and 5, in which the 35 shaft C is shown as held in the divided bearing F G, capable of being adjusted by set-screws H K. By loosening the screw K and screwing in the screw H any desired amount 40 of friction can be obtained.

Instead of using a frictional contact a gear

contact can be employed, as shown at E', Figs. 6 and 7. The cable itself is made tapering, as shown, by means of which backlash is avoided. This tapering form, which is of 45 great importance, can be arranged in several ways. Tapering cores may be provided within the cable made of rawhide, whalebone, or other flexible material, and the cable-wires may be laid upon the same, being wound in 50 opposite directions alternately until the requisite size is built up; or a tapering form can be arranged by starting with a number of wire coils, which of course are wound alternately in different directions, and continuing 55 the entire number for a distance, and then diminishing the number of coils by one consecutively until the smallest desired diameter is obtained. Of course the cable is in any event provided with an external cover L. 60

What I claim as my invention, and desire to secure by Letters Patent, is—

1. The combination, in a motor for rotating a tool or drill, of a driving-shaft, a cable tapering from said driving-shaft toward the 65 tool-holder, and a tool-holder rotated by said tapering cable, substantially as described.

2. The combination, in a motor for rotating a tool or drill, of a driving-shaft, a cable tapering from said driving-shaft toward the 70 tool-holder, a flexible tapering sheath or cover inclosing said cable, and a tool-holder rotated by said tapering cable, substantially as described.

In testimony whereof I have signed my name 75 to this specification in the presence of two subscribing witnesses.

LUCIUS T. SHEFFIELD.
